United States Patent Office

Des. 185,669
Patented July 14, 1959

185,669

DOME FOR A TELESCOPE OR THE LIKE

Paul T. Kaestner, Pittsburgh, Pa., assignor to J. W. Fecker, Inc., Pittsburgh, Pa., a corporation of Pennsylvania

Application March 24, 1958, Serial No. 50,159

Term of patent 14 years

(Cl. D13—1)

Fig. 1

Fig. 2

Des. 185,669

PAGE 2

Fig. 3

Fig. 1 is a front perspective view of a dome for a telescope or the like showing my new design; and

Fig. 2 is a side perspective view thereof looking in a downward direction.

The characteristic features of my new design are shown in full lines in the drawings.

I claim:

The ornamental design for a dome for a telescope or the like, substantially as shown and described.
